(57) **CLAIM**

The ornamental design for a parts detector for industrial robot, as shown and described.

DESCRIPTION

FIG. 1 is a front perspective view of the front, right and top side of a parts detector for industrial robot showing our new design;

FIG. 2 is a rear perspective view of the rear, right and top side thereof;

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a sectional view at a line 9-9 shown in FIG. 3.

FIG. 10 is a sectional view at a line 10-10 shown in FIG. 3.

FIG. 11 is a first reference front view for showing use situation; and,

FIG. 12 is a second reference front view for showing use situation.

The portions of the article in broken lines are shown for illustrative purposes only and form no part of the claimed design.
